UNITED STATES PATENT OFFICE.

CHARLES L. CLARKE AND JOHN LEIGH, OF MANCHESTER, COUNTY OF LANCASTER, GREAT BRITAIN.

APPARATUS FOR LIGHTING GAS BY ELECTRICITY.

SPECIFICATION forming part of Letters Patent No. 240,661, dated April 26, 1881.

Application filed February 14, 1881. (No model.) Patented in England June 1, 1880.

To all whom it may concern:

Be it known that we, CHARLES LEIGH CLARKE and JOHN LEIGH, both residing in Manchester, in the county of Lancaster, and subjects of the Queen of Great Britain and Ireland, have invented Improvements in the Construction of Apparatus for Lighting Gas by Electricity, parts of which improvements are also applicable to other electrical appliances, (for part of which invention we obtained a patent in Great Britain, dated June 1, 1880, No. 2,229,) of which the following is a specification.

The principal object of this invention is to construct a convenient, durable, and portable form of hand lamp or apparatus for lighting gas by means of electric sparks or platinum wire heated by the electric current. This hand lamp or apparatus is especially adapted for use in mills, cotton or other factories, warehouses, and other places where there is a danger of fire from the dropping of a spark if an ordinary lamp or lighted taper be employed for lighting the gas. It may also be used with great advantage in hotels, private dwelling-houses, and other places where it is required to light gas without danger from falling sparks.

To use the electric sparks we employ, by preference, a battery-cell of the special construction hereinafter described, to which is connected an induction-coil, either with or without a condenser.

Figure 1, in the annexed drawings, which form part of this specification, is a vertical section, and Fig. 2 a sectional plan view of the apparatus, showing one modification of battery which we propose to employ.

This battery we prefer to form as follows: We take a small rectangular piece of thin silver-foil, on each side of which we lay a coating (about one-eighth of an inch thick) of chloride of silver in a dry powdered state, keeping the latter in place by wrapping round the whole a single fold of blotting-paper, the silver-foil being provided with a projecting lug, to which one of the wires is to be connected. On each side we then lay a piece of zinc plate of about the same size, each plate being provided with

a projecting lug at one end or side for forming the connection with the other wire. The whole is then wrapped again in one fold of blotting-paper, which is held in position by two or three elastic bands. It is then subjected to pressure in a screw-press or otherwise to solidify the chloride of silver. It is then placed in a small ebonite or wooden box or cell, *a a*, containing the exciting-fluid, which is a saturated solution of chloride of zinc, the quantity of fluid being rather more than will be absorbed by the blotting-paper. A wire, *b b*, is connected to the silver-foil, and a wire, *c c*, is attached to the two zinc plates; but this construction of battery we do not desire to claim in this case, as it is proposed to make it the subject of a separate application.

A condenser may be used with the coil, as shown at *d*, Fig. 2.

The terminals of the induction-coil *e* are carried to two points, *f f'*, respectively, in a suitable short tube, *g g*, these two points being separated by a sufficient space, across which (when the apparatus is working) the electric spark or sparks pass; or, instead of the induction-coil, we employed a fine piece of platinum wire, which is (as is well known) rendered white-hot by the passage of the electric current, such platinum wire being stretched across the above-named tube and connected suitably with the battery.

The tube which carries the ends of the wires from the induction-coil (or, in the other case, the platinum wire) has a guard, *h h*, of wire-gauze attached to it, so that the gas-burner cannot be brought into contact with them and displace and injure them. It is sufficient to connect one of the terminal wires of the coil with any part of the metallic casing of the apparatus for the current of electricity to pass from the point *f* and complete the circuit, the other terminal wire, *f''*, being directly connected with the point *f'*.

The apparatus has a suitable commutator, *i i*, provided, which breaks the circuit, excepting when pressed down by the thumb or finger, so that the whole apparatus is out of action in its normal state. When the commutator

5 *i i* is pressed the circuit is then completed, and a spark or sparks will pass from the end of one wire to the other wire, or the fine platinum wire is heated, and either may be used for lighting the gas.

10 The above form of battery is that which we prefer, although we can use in this lamp any of the other batteries usually employed for working the induction-coils or heating the platinum wire.

15 The whole is inclosed in a casing, of any convenient material, of portable shape, the only parts necessarily projecting outside being the handle, the commutator button or spring, and the tube or casing containing the terminal wires of the coil or the platinum wire.

We claim—

20 1. A portable electrical lighting apparatus containing a battery, induction coil and wires, and provided on the outside with a handle, circuit-closer or commutator, and igniting

points or wire, all substantially as set forth, so that the same hand that carries the apparatus can be used to operate the circuit-closer.

2. An electrical lighting apparatus containing a battery, induction coil and wires, and provided on the outside of the casing with igniting points or wire, and a guard therefor, substantially as set forth.

25 3. In an electrical lighting apparatus, the combination of the igniting points or wire with a casing, tube *g*, and guard *h*, substantially as specified.

30 In testimony whereof we have signed our names to this specification in the presence of two subscribing witnesses.

CHAS. L. CLARKE.
JOHN LEIGH.
